UNITED STATES PATENT OFFICE.

WILLIAM DIETER, OF NEW YORK, N. Y.

STEAM-ENGINE.

SPECIFICATION forming part of Letters Patent No. 746,626, dated December 8, 1903.

Application filed June 4, 1903. Serial No. 160,029. (No model.)

To all whom it may concern:

Be it known that I, WILLIAM DIETER, a citizen of the United States, residing in the borough of Brooklyn, city of New York, county 5 of Kings, and State of New York, have invented certain new and useful Improvements in Steam-Engines, of which the following is a specification, reference being had therein to the accompanying drawings, which form a part thereof.

My invention relates to steam-engines, and more particularly to a type thereof employing a plurality of cylinders.

The object of the invention is to provide a steam-engine which will be simple in construction and which in setting up will require no fine adjustment or fitting of parts nor nice setting of the valve mechanism nor readjustment thereof owing to wear or the 15 replacement of worn parts.

A further object is to provide a steam-engine wherein the steam in the cylinders will be largely exhausted at the end of the direct stroke to reduce the cushioning effect within 25 the cylinder and wherein said cushion will be separately exhausted and controlled to economize power and to insure a steadiness of parts and avoid undue vibration of the engine in running.

30 A further object is to provide an exhaust steam chamber which will also serve as a musifle and which will be so arranged relative to the exhaust-ports as to prevent the clogging thereof through condensation within said chamber or an accumulation of water from cylinder condensation.

40 A further object is to provide an engine of this type having the steam and exhaust ports adjacent to each other, wherein said ports will communicate with the cylinder through a common channel and wherein the working parts of the valves for said ports will be so constructed and arranged as to require no packing against boiler-pressure and wherein 45 any leakage will be conveyed into the exhaust steam chamber.

A still further object is to provide an engine wherein said valves are compactly arranged and to provide means whereby they 50 will be actuated from a single cam-shaft.

A still further object is to provide an engine wherein the cylinder, the steam-chest,

and the exhaust-steam chamber will be so disposed relative to each other as to be capable of being made in a single casting and finished with comparative ease and at small expense. 55

A still further object is to provide an engine the valve-seats of which will require no lubrication and the cylinders of which will be 60 lubricated automatically without employing oil-cups therefor.

The invention consists in providing a steam-engine comprising a group of cylinders, an exhaust-steam chamber surrounding all said 65 cylinders, said cylinders respectively having a steam-port, a valve therefor, a piston having an elongated trunk, ports in each cylinder controlled by said piston discharging into said exhaust-steam chamber, a cushion-controlling exhaust-port, a valve therefor, and means for actuating said steam and said exhaust valves, and in such other novel features of construction and combination of parts as are hereinafter set forth and described, and more particularly pointed out in the claims hereto appended. 70

Referring to the drawings, Figure 1 is a sectional elevation (side) of an engine embodying my invention, showing one of the cylinders and the upper portion of the valve mechanism in section and said valves and the lower portion of said valve mechanism in elevation. Fig. 2 is a front elevation thereof, showing one cylinder in elevation and the valve mechanism 85 therefor in section, another cylinder in section, and the other cylinder in elevation with the valve mechanism removed and the exhaust-steam-chamber cap-plate removed, the piston-rods and valve mechanism appearing only in relation to one cylinder. Fig. 3 is a horizontal section of the cylinder-casting. Fig. 4 is an enlarged view of the upper portion of the valve mechanism and valves, and Fig. 5 is an enlarged plan view of the rocking yoke forming a part of said valve mechanism. 90 95

Like letters refer to like parts throughout the several views.

In steam-engines of this type the various 100 parts appurtenant to each cylinder are duplicated and in the following, in the interests of brevity, a description of but one set of parts will be entered into, except where a part is

common to all cylinders or it is purposed to so construct several elements as to necessarily require a detailed description of the whole.

In the drawings, A indicates the cylinders. 5 A plurality of such cylinders are employed and preferably they are all formed at a single casting with other parts, as will more fully appear hereinafter. Secured to said cylinder-casting is a closed crank-casing B, in which 10 are arranged the main crank-shaft C, the cam-shaft D, the transmission - gearing E, and cranks F, all of which are flooded within said casing and when running dash the oil so as to lubricate themselves and the several cylinders. 15

The transmission-gearing E comprises spur-gears E' and E'', mounted on the shafts C and D, respectively, of equal diameter, and an intermediate spur-gear E³, which arrangement 20 insures a synchronous action of the crank and the cam-shafts.

The pistons G are of ordinary construction, having a long guide-trunk and the usual packing-rings.

25 H indicates the piston-rods.

Preferably I provide a steam-chest a common to all the cylinders A and disposed slightly above and to one side of said cylinders. Separate channels a' communicate 30 with each cylinder and are in communication with the said steam-chest through steam-ports a², having seats thereon for puppet-valves.

Each cylinder A is provided with a main exhaust-port b, so arranged as to be normally 35 closed by the trunk of the piston and opened at substantially the end of the direct stroke of said pistons G. The ports b are disposed on opposite sides of each cylinder and discharge into an exhaust-steam chamber c entirely surrounding all the cylinders contiguous to said ports. I also provide what I term 40 a "cushion-controlling exhaust-valve," closing an exhaust-port d in communication with the channel a' and discharging into an extension c' of the exhaust-steam chamber c. Said port is provided with a valve-seat for a puppet-valve also. The said steam and said cushion - controlling valve - ports are in vertical alignment and the valves closing same, as 45 well as the mechanism actuating said valves, which require such an arrangement of ports will be more fully described hereinafter.

The cylinders A, the exhaust-steam chamber c, the steam-chest a, channel a', and the 50 extension c' of said exhaust-steam chamber are all preferably made of a single casting having core-openings, as e and f, to facilitate the casting process and also the handling and finishing of the said casting. These 55 openings are closed by screw-threaded plugs e' or face-plates f'. The openings f are designated, primarily, to permit the ports in the cylinder b to be drilled in the casting in a convenient and inexpensive manner by working through the said openings, the possibility of which manner of producing is apparent 60 from Figs. 2 and 3.

By having the exhaust-steam chamber c entirely surrounding the cylinders I increase the capacity of this chamber to an extent to 70 cause it to act as a muffle also, and the steam passing through the outlets c² makes little or no noise upon its discharge into the atmosphere. Preferably the lower level of the chamber c is below that of the ports b to prevent the water accumulation from condensation within said cylinders or said chamber from choking or otherwise interfering with 75 said ports.

A puppet-valve g closes the exhaust-port 80 d and is carried by or made integral with a hollow valve-stem g', mounted in a bearing provided in a closure-plug h, secured to the cylinder - casting. The said hollow stem passes through the extension c' of the exhaust-steam chamber and is disposed directly above the cam-shaft D, from which said valve is operated. A second puppet-valve i closes the steam-port a² and is carried by or made integral with a sliding valve-stem, preferably comprised of two independent sections i' i², mounted in the hollow valve-stem g². For convenience of expression hereinafter the said stem actuating the valve g and the said stem actuating the valve i will be designated, respectively, the steam and the cushion-controlling valve-stems. It will be observed that said stems are concentric and work along substantially the same line of force. Beneath said valve-stems g' i' i² is a 100 casting j, carried by the casing B, which is provided with parallel vertical bearings therein, one of which is in alignment with said stems and with an offset bearing j'. Mounted in the said vertical bearings are what I term "cam-pins" k k', which are movable vertically therein. One of these pins, as k, is in direct engagement with the steam valve-stem, and the other pin, as k', indirectly actuates the cushion-controlling valve-stem by means 110 of a rocking yoke l, journaled in the offset bearings j', the opposite arms l' l² of which extend into engagement, respectively, with the pin k' and the cushion-controlling valve-stem g. The latter arm l², as shown in Fig. 115 5, is bifurcated to give clearance of the steam valve-stem i², and the contacting faces of both said arms with the pin k' and the stem g' are curved to facilitate a smooth action at this point. The lower face of the stem g' and the opposed face of the arm l' are extended 120 to give more extended wear-faces.

The various pins and stems heretofore referred to are made a fairly loose sliding fit, so as to avoid the necessity for providing means 125 for oiling these parts.

Each valve mechanism is actuated by means of a set of cams m m' m² m³ n n' n² n³ carried on the cam-shaft D and arranged in pairs so spaced apart as to have the members 130 of each pair engage, respectively, the cam-pins k k'. The valve - motion is controlled solely through the said set of cams and consequently the different speeds and the re-

verse, as well as the neutral or cut-off, may be so controlled. To control the engine, therefore, any desired means may be employed to shift the cam-shaft D laterally to cause different cams to act upon said pins $k k'$. Such mechanism and its mode of operation being well known in this art, it is not herein shown nor described.

Steam is admitted to the steam-chest a through the steam-pipe o .

All contacting faces of the above-described valve-controlling mechanism are preferably hardened to prevent undue wear on else hardened contact-points are secured thereto.

25 In a steam-engine constructed as above it is unnecessary to pack the various parts against steam leakage. The pistons G are, as heretofore stated, provided with the ordinary piston-rings, and the only other point 20 at which leakage is possible is between the cushion-controlling valve-stem and the steam valve-stem $i^1 i^2$, as with puppet-valves there is substantially no wear on the valve-seats to cause leakage there. To guard against 25 the leakage first mentioned as much as possible, I dish out the upper face of the cushion-controlling valve g at g^2 to form a waterpacking about the steam valve-stem i where it enters said hollow stem g' . It is found, 30 however, that there is always a slight leakage at this point, and to dispose of this I provide what may be termed a "supplemental exhaust," consisting of a small recess g^3 , formed on the inside of the cushion-controlling valve- 35 stem g' , which discharges into the chamber c' through openings g^4 in said stem. Hence any leakage is discharged into the general exhaust-chamber. The closure-plug h is similarly dished out about the said cushion-controlling valve-stem to form a water-packing 40 against exhaust-pressure, which form of packing is found to be efficient in this connection. The steam valve-stem $i^1 i^2$ is made sectional to guard against breaking strains occurring 45 about that point.

I provide suitable springs $p p'$, acting, respectively, against the plug e' and valve i and against said valve and the valve g to aid in restoring these parts to their seats, although 50 the steam-pressure as a rule is sufficient to insure a quick return thereof.

The operation of steam-engines of this general type is sufficiently well known in the art to render a detailed description thereof unnecessary except in so far as appertains directly to the novel details of construction heretofore described. To start the engine, supposing the cam-pins $k k'$ to be on cams m n , respectively, (the neutral cams whereby the steam-valve is closed and the cushion-controlling valve is open.) By shifting the shaft D to the right the pin k rides upon the cam m' of one of the sets of cams and the pin k' rides upon the cam n' of the same set of cams. 65 This raises the pin k , which movement through the steam valve-stem $i^1 i^2$ opens the steam-valve i and admits steam from the steam-chest

a to at least one of the cylinders A to start the engine. The same action closes the cushion-controlling valve g in a manner to be described. The rotation of the crank-shaft D through the transmission-gearing E imparts similar motion to the shaft C, which successively opens the other steam-valves i and actuates the cushion-controlling valves of the remaining cylinders, and the engine speed may be further controlled, as heretofore stated, by a further lateral movement of said shaft D. The further description of the mode of operation will be confined to a single cylinder. 80 As the puppet-valve i is opened against the tension of the spring p steam is admitted to the channel a' and thence to the cylinder A. The pressure of the said steam upon the valve g serves to prevent leakage at that point. As 85 the steam enters the cylinder the piston G moves forward until it reaches the approximate limit of its direct stroke, when the ports in the cylinder b , which are normally closed by the guide-trunk of said piston, are opened 90 and the steam in the cylinder is exhausted to an extent to materially reduce the steam-cushion resulting from the return stroke of the said piston and any water in the cylinder is blown out of said ports. Upon the return 95 movement of said piston and the continued rotation of the cam-shaft D one of the cams n' thereon raises the cam-pin k' , which in turn, by contact with the arm l^2 of the rocking yoke l rocks said yoke. Vertical 100 movement is thereby imparted to the cushion-controlling valve-stem g' through the other arm l^1 of said yoke, which opens the valve g , thus accomplishing the complete exhaustion of the steam forming the cushion 105 prior to the admission of more steam to the cylinder. By this arrangement of parts the cylinder-exhaust is accomplished in a manner to minimize the resistance within each cylinder during the return stroke, the exhaust 110 through both the main and the cushion-controlling exhaust-ports being against exhaust-steam pressure only and an accumulation of water in the cylinder being prevented.

In setting up the engine the extent of the 115 cushion within the cylinder may be controlled to a nicety by regulation, the cams actuating the cushion-controlling valve g as the interval of operation of said valve controls said cushion.

The exhaust-steam passing through the ports b is discharged directly into the exhaust-steam chamber c , which, as heretofore stated, also acts as a muffle. That passing through the valve g passes to said exhaust-steam 125 chamber through the extension c' thereof, and the contents of said chamber are discharged into the atmosphere through the pipe c^2 , or, if desired, into a condenser.

If any of the working parts become partly 130 or wholly inoperative, they may be replaced at small expense by similar parts without affecting the other working parts of the engine or requiring any high degree of skill to effect

the change. The various parts are designedly so made that duplicate parts may be so used and applied without necessitating a readjustment of any valve mechanism which would require the skill of a mechanic or engineer.

Primarily the engine is designed for use on an automobile, and to best serve this purpose it is desirable that it be so constructed and that the parts be so arranged as to require little or no attention while in use. The engine is therefore so designed as, when once set up in the shop, to require no further adjustment, to not become disordered through service except through the inevitable wear, to require no repacking at intervals, and, in fact, require no attention from skilled mechanics or engineers to keep it in condition.

The engine constructed as heretofore described runs smoothly with little vibration and under high pressures, is simple in its design, and is composed of parts so arranged as to not be readily susceptible of getting out of order through use.

It is not my intention to limit the scope of this patent to the specific design of engine herein shown and described, as it is apparent that such may be modified and yet incorporate therein the essential details of the invention.

Having described the invention, what I claim as new, and desire to have protected by Letters Patent, is—

1. In a steam-engine, a group of cylinders, an exhaust-steam chamber surrounding all said cylinders, said cylinders respectively having a steam-port, a valve therefor, a piston having an elongated trunk, ports in each cylinder controlled by said piston discharging into said exhaust-steam chamber, a cushion-controlling exhaust-port, a valve therefor, and means for actuating said valves respectively.

2. In a steam-engine, a group of cylinders, an exhaust-steam chamber surrounding all said cylinders, said cylinders respectively having a steam-port, a valve therefor, a piston having an elongated trunk, ports in each cylinder controlled by said piston discharging into said exhaust-steam chamber at a point above the lower level of said chamber, a cushion-controlling exhaust-port, a valve therefor, and means for actuating said valves respectively.

3. In a steam-engine, a group of cylinders, an exhaust-steam chamber surrounding all said cylinders, said cylinders and said chamber being formed in a single casting, said cylinders respectively having a steam-port, a valve therefor, a piston having an elongated guide-trunk, ports in each cylinder controlled by said piston discharging into said exhaust-steam chamber, a cushion-controlling exhaust-port, a valve therefor, and means for actuating said valves respectively.

4. In a steam-engine, a group of cylinders, a steam-chest common to all said cylinders, an

exhaust-steam chamber surrounding all said cylinders, said cylinders respectively having a steam-port, a piston having an elongated trunk, ports in each cylinder controlled by said piston discharging into said exhaust-steam chamber, a cushion-controlling exhaust-port in alignment with said steam-port, a puppet-valve therefor, a hollow stem therefor, journaled in an extension of said cylinder-casting, a steam-valve, a stem therefor journaled in said first-mentioned stem and concentric therewith, and means for alternately sliding said stems to actuate said valves.

5. In a steam-engine, a cylinder having a steam-port, a valve therefor, a piston working in said cylinder, a main exhaust-port so disposed in said cylinder as to be opened toward the end of the direct piston-stroke, a cushion-controlling exhaust-port, a valve therefor, a hollow cushion-controlling valve-stem journaled in an extension of said cylinder-casting, a sectional steam valve-stem journaled in said first-mentioned stem and concentric therewith, and means for alternately sliding said stems to actuate said valves.

6. In a steam-engine, a cylinder, a piston working therein, a steam and an exhaust port, a common channel therefor communicating with said cylinder, valves for said ports respectively and means for alternately opening said valves.

7. In a steam-engine, a cylinder, a piston working therein, a steam and an exhaust port in alignment with each other, a common channel therefor communicating with said cylinder, valves for said ports respectively, a hollow exhaust valve-stem journaled in an extension of said cylinder-casting, a steam valve-stem journaled in said hollow stem and concentric therewith and means for alternately actuating said stems to open said valves.

8. In a steam-engine, a cylinder, a piston working therein, a steam and an exhaust port in alignment with each other, a common channel therefor communicating with said cylinder, valves for said ports respectively, a hollow exhaust valve-stem journaled in an extension of said cylinder-casting, a sectional steam valve-stem journaled in said hollow stem and concentric therewith and means for alternately actuating said stem to open said valves.

9. In a steam-engine, a cylinder, a piston working therein, a steam and an exhaust port in alignment with each other, a common channel therefor communicating with said cylinder, valves for said ports respectively, a hollow exhaust valve-stem journaled in an extension of said cylinder-casting, a steam valve-stem journaled in said hollow stem and concentric therewith, and means for alternately actuating said stem to open said valves comprising a plurality of cams means for actuating said cams, a rocking yoke jour-

- naled above said cams, a plurality of pins each adapted to engage one of said cams, said pins respectively engaging said steam valve-stem and one arm of said rocking yoke, 5 the other arm of said yoke being bifurcated to straddle said steam valve-stem and engage said exhaust valve-stem.
10. In a steam-engine, a cylinder, a piston working therein, a steam and an exhaust port in alinement with each other, a common channel therefor communicating with said cylinder, valves for said ports respectively, a hollow exhaust valve-stem journaled in an extension of said cylinder-casting, a steam 15 valve-stem journaled in said hollow stem and concentric therewith, and means for alternately actuating said stems to open said valves comprising a plurality of cams, means for actuating said cams, a casting having parallel vertical bearings therein disposed directly above said cams and an offset bearing thereon, a rocking yoke journaled in said offset bearing, a plurality of pins mounted in said vertical bearings each adapted to engage one 20 of said cams, said pins respectively engaging said steam valve-stem and one arm of said rocking yoke, the other arm of said yoke being bifurcated to straddle said steam valve-stem and engage said exhaust valve-stem, the contact-faces of said yoke-arms being curved. 25
11. In a steam-engine, a cylinder, a piston working therein, a steam and an exhaust port in vertical alinement with each other, a common channel therefor communicating with said cylinder, puppet-valves for said ports respectively, a hollow exhaust valve-stem journaled in an extension of said cylinder-casting, a steam valve-stem journaled in said hollow stem and concentric therewith and means for alternately raising said stems to open said valves, said exhaust-valve being provided with a dished upper face adjoining said steam valve-stem whereby a water-packing is provided. 30
45. 12. In a steam-engine, a cylinder, a piston working therein, a steam and an exhaust port in vertical alinement with each other, a common channel therefor communicating with said cylinder, an exhaust-steam chamber below said channel, puppet-valves for said ports respectively, a hollow exhaust valve-stem journaled in an extension of said cylinder-casting and passed through said exhaust-steam chamber, a steam valve-stem journaled in said hollow stem and concentric therewith, and means for alternately raising said stems to open said valves, said exhaust-valve being provided with a dished upper face adjoining said steam valve-stem whereby a water-packing is provided and said hollow exhaust valve-stem having supplemental exhaust-ports therein discharging into said exhaust-steam chamber. 55
60. 13. In a steam-engine, a cylinder, a piston therefor, a steam and an exhaust port in alinement with each other and opening into a channel communicating with said cylinder, an exhaust-steam chamber below said channel, puppet-valves for said ports respectively, a hollow exhaust valve-stem journaled in an extension of said cylinder-casting and passing through said exhaust-steam chamber, a steam valve-stem journaled in said hollow stem and concentric therewith and means for alternately sliding said stems to actuate said valves, said hollow exhaust valve-stem having a supplemental exhaust comprising an interior recess and exhaust-ports therefor discharging into said exhaust-steam chamber. 70
75. 14. In a steam-engine, a cylinder, having a steam-port, a valve therefor, a piston working in said cylinder, a main exhaust so disposed in said cylinder as to be opened toward the end of the direct piston-stroke, a cushion-controlling exhaust-port in alinement with said steam-port, a valve therefor, a hollow exhaust valve-stem journaled in an extension of said cylinder-casting, a steam valve-stem journaled in said hollow stem and concentric therewith, and means for alternately raising said stems to open said valves comprising a plurality of cams, means for actuating said cams, a rocking yoke journaled above said cams, a plurality of pins each adapted to engage one of said cams, said pins respectively 80
85. 90. 95. 100. 105. 110. 115. 120. 125. 130.
15. In a steam-engine, a group of cylinders, an exhaust-steam chamber surrounding all said cylinders, said cylinders and said chamber being formed in a single casting, said cylinders respectively having a steam-port, a valve therefor, a piston having an elongated guide-trunk working in said cylinder, ports in each cylinder controlled by said piston discharging into said exhaust-steam chamber, a cushion-controlling exhaust-port in alinement with said steam-port, a valve therefor, a hollow exhaust valve-stem journaled in an extension of said cylinder-casting, a steam valve-stem journaled in said hollow stem and concentric therewith, and means for alternately raising said stems to open said valves comprising a plurality of cams, means for actuating said cams, a rocking yoke journaled above said cams, a plurality of pins each adapted to engage one of said cams, said pins respectively engaging said steam valve-stem and one arm of said yoke, the other arm of said yoke being bifurcated to straddle said steam valve-stem and engage said exhaust valve-stem. 110
16. In a steam-engine, a group of cylinders, a steam-chest common to all said cylinders, an exhaust-steam chamber surrounding all said cylinders and common thereto having openings on each side thereof opposite each cylinder, an individual extension of said exhaust-steam chamber and an individual channel disposed between said steam-chest and said extension for each cylinder, all made in a single casting, closure-plates for said open-

ings, said cylinders respectively having a steam-port establishing communication between said steam-chest and said channel, a piston having an elongated guide-trunk working therein, ports in each cylinder controlled by said piston discharging into said exhaust-steam chamber, a valve for said steam-port, a cushion-controlling exhaust-port in alignment with said steam-port establishing communication between said channel and said exhaust-steam-chamber extension, a valve therefor, a hollow cushion-controlling exhaust valve-stem journaled in and passing through said extension, a steam valve-stem journaled in said hollow stem and concentric therewith and means for alternately actuating said stems to open said valves, said cushion-controlling exhaust valve-stem being provided with a dished upper race adjoining said steam valve-stem whereby a water-packing is provided and said hollow stem having supplemental exhaust-ports within said exhaust-steam-chamber extension discharging thereinto.

17. In a steam-engine, a group of cylinders a steam-chest common to all said cylinders, an exhaust-steam chamber surrounding all said cylinders and common thereto having openings on each side thereof opposite each cylinder, an individual extension of said steam-exhaust chamber and an individual channel disposed between said steam-chest and said extension for each cylinder all made in a single casting, closure-plates for said openings, said cylinders respectively having a steam-port establishing communication between said steam-chest and said channel, a piston having an elongated guide-trunk working therein, ports in each cylinder controlled by said piston discharging into said exhaust-steam chamber, a puppet-valve for said steam-port, a cushion-controlling exhaust-port in alignment with said steam-port establishing communication between said channel and said exhaust-steam-chamber extension, a puppet-

valve therefor, a hollow cushion-controlling exhaust valve-stem journaled in and passing through said extension, a steam valve-stem journaled in said hollow stem and concentric therewith and means for alternately actuating said stems to open said valves, said cushion-controlling exhaust valve-stem being provided with a dished upper race adjoining said steam valve-stem whereby a water-packing is provided and said hollow stem having supplemental exhaust-ports within said exhaust-steam-chamber extension discharging thereinto.

18. In a steam-engine, a cylinder, a piston therefor, a steam and an exhaust port aligned with each other, puppet-valves for said ports respectively, a hollow exhaust valve-stem journaled in an extension of said cylinder-casting, a steam valve-stem journaled in said hollow stem and concentric therewith, and means for alternately sliding said stems to actuate said valves comprising a plurality of cams, means actuating said cams, a rocking yoke journaled above said cams, a plurality of pins each adapted to engage one of said cams, said pins respectively engaging said steam valve-stem and one arm of said rocking yoke, the other arm of said yoke being bifurcated to straddle said steam valve-stem and engage said exhaust valve-stem.

In witness whereof I have hereunto affixed my signature this 22d day of May, 1903, in the presence of two witnesses.

WILLIAM DIETER.
